Order of M. Chaffee for Making of India Rubber Mail Bag

The following are the directions given by Mr. Chaffee and making part of the same, containing a description of the mode of making India Rubber Mail Bag, based upon his experience in the manufacture of constructing India Rubber Mail Bag of Cloth and wool handling Bags.

To all whom it may concern: Be it known that S. Odious & M. Chaffee of Newbury in the County of Norfolk and Commonwealth of Massachusetts have invented a new and useful improvement, being a mode of constructing India Rubber Mail Bag and Woolen Bags, and that the following is a full and exact description of the same and invention.

Take cloth of any suitable kind that is covered with India Rubber, from which extract the pattern for the lining of the mail or woolen Bag, two pieces, specially alike in size and shape, and of such dimensions as is required, but opposite to each other and a certain space, the main body, as to form a neck of sufficient width to admit letters, parcels, &c. & then place the two pieces so as one upon the other, the cloth surface forming the inside of the bag, the coating of India Rubber being on the outside. The two pieces are then bound together by connecting a strip of cloth covered on both sides with India Rubber, along the edges and lapping one on each side about half an inch or more. I then cut two more pieces of India Rubber, coated on both sides with India Rubber, of the same shape as the lining but about half an inch longer all round. These two last named pieces from the outside of the bag and are firmly connected to the lining before mentioned. And the outside pieces being longer will consequently be connected together, outside of the lining forming an edge outside of the lining all round the bag. The neck of the bag I make from silk to twelve inches in length and from right to twelve inches in width according to the size of the bag. The neck must be lined with India Rubber by 3L 43, for together with lining to make the neck eight inches when it is closed. The neck is closed by gathering and the neck is firmly and closely and in tight corners and the neck is closed by two pieces of India Rubber upon each side of the

make of the bag, the straps, consisting of a piece of India Rubber cloth, which is covered over by a piece of leather, should be distant from the mouth as is required for the safety. The straps are formed and placed in such a manner, as that there is a wide sufficient distance between them on the other side, and having eyes or holes in them which will admit a rod of steel or iron to pass through them and unite them together and thus fasten and secure the mouth of the bag. The rod should have a head at one end and at the other a hook, staple for the reception of a Padlock too large to be drawn thro' the holes in the straps. The mouth may be closed by strap and springs. The same parts, shutting together with the edges of the mouth of the bag between them, and by causing other parts and contrivances, not saying my invention. My claim is, ^{the arrangement} the mode of constructing and manufacturing water proof bags from India Rubber cloth as above described. I declare this the day of December in the year of our Lord One Thousand Eight hundred and thirty three.

Testimony that the foregoing is a true and
